UNITED STATES PATENT OFFICE.

ERICH J. PATELSKI, OF CHICAGO, ILLINOIS.

SWING-SPOUT FAUCET.

Application filed March 5, 1927, Serial No. 172,978. Renewed February 2, 1928.

This invention relates to improvements in swing spout faucets, and more particularly to a faucet especially designed for kitchen sinks, dish washers, and like appliances utilizing running water for cleaning or rinsing.

The object of the invention is to provide a novel departure from the more common type of so-called swing spout faucet characterized by a spout which may be swung horizontally to any desired position within an arc of about 180°. The novel construction herein disclosed provides for two spouts, with the further feature that either may be used independently or the two may be used simultaneously but so arranged that the swinging of either or both arms into a predetermined position automatically closes off the water supply thereto and independently of the usual hot and cold water shut-off cocks ordinarily provided with such faucet installations.

The further improved features of construction will be hereinafter disclosed in connection with the accompanying drawing, in which

Figure 1 is a top plan view of a complete faucet installation embodying the novel features of the invention.

Figure 2 is a front view in elevation of the faucet installation.

Figure 3 is an enlarged detail view in vertical section taken on line 3—3 of Figure 1.

Figure 4 is a detail view in cross section taken on line 4—4 of Figure 3; and

Figure 5 is a detail view showing the spray head in section.

The faucet has been illustrated as applied to a kitchen sink, as represented by the back 1 which extends above the bowl and drain board of the ordinary cast iron enameled sink. The faucet is preferably located centrally above the bowl of the sink with its pipe connections behind the back 1, the main portion or body of the faucet extending forwardly of the back and thence upwardly, being provided with an annular flange 2 bearing flush against the back and concealing an opening 1a therein through which a threaded stem 3 projects. This stem 3 connects with a T-fitting 4 having branch pipes 5, 5 leading to the hot and cold water supplies. Valves or cocks 6—6 are located in said pipes, their valve stems extending through the back and provided with the usual form of handles 7, 7 located on either side of the

faucet. The valves and fittings used with the faucet may be of any approved design and form no part of the invention, although where hot and cold water is supplied, it is preferable to install the faucet in the manner illustrated, both to regulate the temperature of the water discharged at the faucet and to close off the water entirely when the faucet is not in use.

Referring now more in detail to the construction of the faucet, the base portion 8 thereof is generally spherical in shape and hollow, being preferably cast in one piece with the flange 2 and threaded stem 3 at the rear. Also integral with the base portion is a vertical neck portion 9 of a concavo-convex external contour and having a convergent internal passage becoming uniform and extending upwardly beyond said neck portion 75 in the form of a tubular extension or stem 10 closed at its upper end.

The upper portion of the neck 9 is slightly divergent and terminates in an upwardly facing shoulder 9a surrounding the base of the stem 10. Mounted on the stem are two ball shaped collars 11 and 12, the lower collar bearing upon the shoulder 9a and the upper collar 12 bearing upon said lower collar. These collars are not spherical but are flattened at their upper and lower ends to provide bearing surfaces. These collars are also bored axially to fit snugly on the stem 10 which projects a short distance above the upper collar and is surmounted by a nut 13 having screw-threaded connection with the stem and preferably held against rotation by a lock screw 14 extending axially through the top of the nut and tapped into the end of the stem.

Threaded into the lower collar 11 is a faucet arm or spout 15 extending horizontally at right angles to the stem 10. Likewise threaded into the upper collar 12 is another faucet arm or spout 16 just above the first-mentioned spout 15. These two spouts swing with their respective collars in parallel planes but without interfering with each other, for the reason that the lower pipe is somewhat shorter than the upper arm and terminates in a downwardly turned end 15a from which a solid stream of water will issue. The upper arm 16 is bent downwardly beyond the end of the shorter spout and has a spray head 17 fixed to its end preferably by a threaded connection as shown in Figure 5, so that it can be removed

for cleaning. Thus the lower arm swings within the arc of the upper arm and without interference.

The collars 11 and 12, as already stated, are pivoted on the stem 10 and suitably packed to prevent leakage. This is accomplished by providing at the several joints where leakage occurs, interfitting annular tongues and grooves 18 and 19. These joints occur between the lower face of the collar 11 and the shoulder 9^a of the neck 9, between the contacting faces of the two collars, and between the upper end of the upper collar and the nut 13. Since the same arrangement is used at each joint, the following description applies to all. For instance, at the lowermost joint an annular tongue 18, square in section, is provided on the underface of the collar 11 between the outer and inner edges, this tongue fitting into a complementary annular groove 19 in the shoulder 9^a. At the bottom of the groove is a thin ring 20 of suitable packing material and, similarly, between the surfaces on either side of the tongue and groove are concentric packing rings 21, 21. This same arrangement is repeated at each joint. The joints are made tight by the nut 13 which is turned down until the packing is compressed sufficiently to prevent leakage.

It has also been pointed out that the spouts may be shut off by swinging the same into a predetermined position. This is made possible by the provision of ports 22-22 in the stem 10 adapted to register with the inner ends of each spout. Thus as shown in Figure 4, the collars are bored radially to form passages into which the spouts are threaded, these radial passages intersecting the axial bores of the collars so that they open flush against the cylindric surface of the stem. The ports 22-22 in the stem are preferably located so that when either spout is swung to its forward position, that is, at right angles to the back 1, it registers with its respective port and water will flow providing the valves 6, 6 are turned on. Similarly, when either spout is swung to the right or left to a position parallel with the back 1 and hence out of the way, it will not register with its port and the flow is shut off. Owing to the reduced diameter of the stem, the ports 22-22 are elongated longitudinally to obtain the maximum port area. However, the shape or location of either port may be varied in order to obtain flow at different angular positions or throughout different arcs of the arms. For instance, it may be desired that the spray spout 16 shall only be turned on when its arm is immediately over the bowl and therefore at right angles to the back 1, while flow from the other spout may be desired at several positions within an arc of say 45° on either side of a forward position.

This can be readily provided for by increasing the circumferential dimensions of the port or ports.

Another feature of construction that is quite desirable, is means for preventing the spouts from moving together when one of them is swung, due to the frictional contact between them. This is accomplished by forming an elongated vertical cavity 23 in the internal bore of each of the collars 11 and 12 diametrically opposite the spout. Within this cavity is placed a leaf spring 24 slightly shorter than the length of the cavity and bowed outwardly at its central portion toward the stem. Formed in the outer surface of the stem and in the corresponding positions as the springs 24, are series of elongated depressions 25, one of each series being located opposite the ports 22 and two removed 90° from the ports. The vertical edges of these depressions are rounded so that the spring may readily slide into and out of the recesses as it comes opposite the same in the swinging of the faucet arms, thus retarding the swinging movement rather than locking them against movement.

The operation of the faucet is obvious. When either or both spouts are swung to the left or right against the back 1 of the sink, their respective ports are closed. From either of these closed positions, one or the other or both spouts may be swung outwardly at right angles to the closed position (or an intermediate position) and the ports would be open. Thus it will be seen that the faucet is equipped with valves which control the discharge of water by swinging the spouts. However, since hot and cold water are ordinarily supplied to the faucet, additional valves 6-6 are preferably used, not only to completely shut off the supply to the faucet, but also to regulate the temperature of the water by controlling the volumes of hot and cold water delivered to the faucet.

This type of faucet is especially advantageous and convenient for use in kitchen sinks for the spray cleaning of dishes, in washing or rinsing, cleaning of vegetables and many other uses where a spray is preferable to a solid stream. At the same time, the ordinary solid stream is available for the ordinary water withdrawals, as for instance, the filling of receptacles and cooking utensils.

Again, the faucet is particularly desirable for use in connection with dish washing apparatus of the type built into the sink. Thus with the spray arm of a length to be swung over the bowl in which the dishes are washed, hot water can be sprayed onto the dishes during the washing and rinsing operations. This arrangement is far more convenient than the usual spray nozzle attached

to a rubber hose which must be held in the hand and directed onto the dishes, since it leaves the operator entirely free to do other tasks while the washing operation is in progress. At the same time, water can be drawn from the faucet through the other arm, so that the spraying does not monopolize the entire supply.

Having set forth a preferred embodiment 10 of the invention and the merits thereof, I claim:

1. In a faucet of the character described, the combination of a fixed portion communicating with a source of water supply, and a 15 plurality of spouts pivotally mounted on said fixed portion to swing independently of each other in parallel planes adapted to communicate with said fixed portion.

2. In a faucet of the character described, 20 the combination of a base portion communicating with a source of water supply, a plurality of spouts pivotally mounted on said base portion to swing independently of each other, and means operative in the swinging 25 of said spouts for controlling the discharge of water therefrom.

3. In a faucet of the character described, the combination of a base portion adapted 30 for connection with a source of water supply and provided with a tubular extension closed at its free end, a plurality of spouts pivotally mounted on said extension to swing independently of each other, said extension having ports adapted to register with said 35 spouts in one position of swinging movement thereof.

4. In a faucet of the character described, the combination of a body portion adapted 40 for connection with a source of water supply and having a tubular extension provided with longitudinally spaced lateral ports, a plurality of spouts pivotally mounted on 45 said extension, each of said spouts being adapted to register with one of said ports in predetermined positions of angular movement, one of said spouts being shorter than the other to permit said spouts to swing independently of each other.

5. In a faucet of the character described, 50 the combination of a body portion adapted for connection with a source of water supply and having a tubular extension closed at its free end, a plurality of spouts pivotally mounted on said extension and adapted to swing independently of each other in parallel planes and to communicate with said extension in one position, and having their 55 end portions bent at right angles in the same direction, one of said spouts being longer to permit the same to swing freely of the other spout.

6. In a faucet of the character described, 60 the combination of a body portion adapted for connection with a source of water supply and having a tubular extension, a plu-

rality of spouts pivotally mounted on said extension to swing independently of each other in parallel planes and about the axis of said extension, said spouts comprising 70 collars fitting on said extension and having radial passages connected with said spouts, said extension having ports adapted to register with said passages in one position of swinging movement of said spouts and to be closed by said collars in other position 75 of swinging movement of said spouts.

7. In a faucet of the character described, the combination of a body portion adapted 80 for connection with a source of water supply and having a tubular extension, a pair of spouts pivotally mounted on said extension and adapted to swing independently of each other in parallel planes and to communicate with said extension, one of said spouts being longer than the other, and a spray 85 head mounted at the end of one of said spouts.

8. In a faucet of the character described, the combination of a body portion, a pair 90 of spouts mounted on said body portion and adapted to swing about the same axis in parallel planes and to communicate with said body portion in one position, and tension means acting on said spouts to retard the swinging of one in the movement of the 95 other of said spouts.

9. In a faucet of the character described, the combination of a body portion having a tubular extension, a pair of spouts pivotally mounted on said extension in frictional contact with each other and adapted to swing about a common axis in parallel planes and to communicate with said body portion in one position, and means interposed between one of said spouts and said extension for retarding its movement when the other spout 100 is swung.

10. In a faucet of the character described, the combination of a body portion having a tubular extension, a pair of spouts pivotally 110 mounted one above the other on said extension and comprising annular portions fitting around said extension in bearing engagement with each other, said extension having ports adapted to communicate with said spouts in predetermined angular positions thereof, and springs mounted in said annular portions of said spouts and frictionally engaging said extension to overcome the tendency 115 of said spouts to swing together.

11. In a faucet of the character described, the combination of a body portion having a tubular extension, a pair of spouts pivotally mounted one above the other on said extension and comprising collars fitting around 120 said extension in frictional bearing contact with each other, said spouts in one position adapted to communicate with said extension, a leaf spring mounted in an internal cavity formed in each of said collars and 125

- adapted to yieldingly engage angularly spaced depressions in the surface of said extension to hold one of said spouts against movement in the swinging of the other.
- 5 12. In a faucet of the character described, the combination of a body portion having a tubular extension of reduced diameter and an annular shoulder at the base of said extension, a pair of spouts comprising collars 10 fitting on said extension in bearing contact with each other, said spouts in one position adapted to communicate with said extension, one of said collars bearing against said shoulder, a nut surmounting said extension 15 and bearing against the other of said collars, packing rings located between said collars, shoulder and nut, and tension members carried by said collars and yieldingly engaging said extension to retard the free swinging 20 movement of said spouts.
13. In a faucet of the character described, the combination of a body portion having a tubular extension of reduced diameter and an annular shoulder at the base of said extension, a pair of spouts comprising collars 25 fitting on said extension in bearing contact with each other, said spouts in one position adapted to communicate with said extension, one of said collars bearing against said 30 shoulder, and a nut having threaded engage- ment with said stem and bearing upon the other of said collars, said collars, nut and shoulder having interfitting annular tongues and grooves, and packing rings inserted at the bottom of said grooves. 35
14. In a faucet of the character described, the combination of a body portion having a tubular extension of reduced diameter and an annular shoulder at the base of said extension, a pair of spouts comprising collars 40 fitting on said extension in bearing contact with each other, said spouts in one position adapted to communicate with said extension, one of said collars bearing against said shoulder, a nut surmounting said extension 45 and bearing against the other collar, there being formed annular bearing faces between said collars, nut and shoulder having annular interfitting tongues and grooves intermediate the inner and outer edges thereof, 50 packing rings mounted in the bottom of said annular grooves and between the bearing faces adjacent thereto, and tension members carried by said collars and yieldingly engaging angular spaced depressions in said 55 extension to retard the free swinging movement of said spouts.

Signed at Chicago, Ill., this 3rd day of March, 1927.

ERICH J. PATELSKI.
